COMPOUND KNITTING NEEDLE

Davis Marinsky, Bronx, N. Y.; Louis H. Morin
executor of the Estate of said Davis Marinsky,
deceased

Application January 3, 1948, Serial No. 431

7 Claims. (Cl. 66—117)

1

This invention relates to needles used for knitting. More particularly, the invention deals with a construction of what I term a compound needle, wherein a plurality of needles are disposed one within the other in telescoped relationship, as well as detachable relationship, so that each needle of the assemblage can be independently used and, at all times, a head is provided at one end of the needle to prevent the yarn from displacement on the needle.

The novel features of my invention will be best understood from the following description, when taken together with the accompanying drawing, in which certain embodiments of the invention are disclosed and, in which, the separate parts are designated by suitable reference characters in each of the views, and in which:

Fig. 1 is an enlarged longitudinal section through a compound needle made according to my invention with parts of the construction broken away; and

Fig. 2 is a side view showing one member of the needle partially extended.

In the use of knitting needles, difficulty has been experienced in keeping track of several needles of different sizes, particularly with respect to diameters. The purpose of my invention is to provide what I call a compound needle, wherein a plurality of needles are kept in an assemblage, the separate needles being telescopically detachable one with respect to the other, so that each size needle of the assemblage can be individually used, while at all times, providing on each needle a head, preventing displacement of yarn from the needle.

My improved compound needle comprises three telescoping needle members, namely an inner small diameter solid needle 10, around which is arranged a next larger or intermediate needle 11, outwardly of which is disposed a large diameter needle 12. In constructing the compound needle, the intermediate needle 11 has a pressed fit in an enlarged head or ferrule 13, as seen at 14 and, if desired, the parts may be cemented or otherwise secured together. The ferrule has, at one end, a reduced internally threaded sleeve portion 15, in connection with which the threaded end 16 of the outer needle 12 is adapted to be coupled. The ferrule or head 13, has, at its opposite end, a reduced outwardly directed split spring tube extension 17 formed by diametrically opposed splits, one of which is shown at 18 and the bore 19 of the spring sleeve extension 17 is adapted to firmly engage the shank of the needle 10 adjacent the head 20 of said needle. The needle 10 has a re-

2

duced end portion 21, which seats in the head 20 and is riveted-over or headed, as seen at 22, in securing the head 20 in position. The head 20 is kept within the diameter of the head or ferrule 13, as will clearly appear from a consideration of Fig. 1. Each needle 10, 11 and 12 terminates at its free end in a bevel or point 10', 11' and 12' as clearly seen in Fig. 1, so that each needle becomes a usable needle in the process of knitting or the like. While the needles may be composed of any desired material, it is preferable that they be composed of plastic material and, in this respect, different colored plastics can be employed, for example, the needle 10, including its head 20, may be composed of a blue plastic, the needle 11, including the head or furrow 13 can be composed of red and the needle 12 of white or any other contrasting color.

When it is desired to use the needle 10, it is simply forcibly removed from the end of the compound assemblage, leaving the needles 11 and 12 in their assembled relationship to each other. On the other hand, when it is desired to use a needle of the size defined by the intermediate needle 11, then the needle 12 is simply removed. On the other hand, when the needle 12 is to be used, the complete assemblage will be maintained. With this construction, it is quite apparent that a plurality of needles of different sizes can be maintained in a compact relationship one with respect to the other and the possibility of loss of needles of different sizes is minimized.

Having fully described my invention what I claim as new and desire to secure by Letters Patent is:

1. A compound knitting needle of the character described comprising a plurality of telescoping needle members, means at one end of the needle members for maintaining all of the needle members in collapsed assembled relationship one with respect to the other, said means forming a head for predetermined tubular needle members, the innermost needle member being in the form of a rod, and said innermost needle member having an independent head disposed beyond the first named head.

2. A compound knitting needle of the character described comprising a plurality of telescoping needle members, means at one end of the needle members for maintaining all of the needle members in collapsed assembled relationship one with respect to the other, said means forming a head for predetermined tubular needle members, the innermost needle member being in the form of a rod, said innermost needle member having an in-

dependent head disposed beyond the first named head, and one of the tubular needle members being permanently secured to the first named head.

3. A compound knitting needle of the character described comprising a plurality of telescoping needle members, means at one end of the needle members for maintaining all of the needle members in collapsed assembled relationship one with respect to the other, said means forming a head for predetermined tubular needle members, the innermost needle member being in the form of a rod, said innermost needle member having an independent head disposed beyond the first named head, one of the tubular needle members being permanently secured to the first named head, and another tubular needle member being detachable with respect to the first named head.

4. A compound knitting needle of the character described comprising a plurality of telescoping needle members, means at one end of the needle member for maintaining all of the needle members in collapsed assembled relationship one with respect to the other, said means forming a head for predetermined tubular needle members, the innermost needle member being in the form of a rod, said innermost needle member having an independent head disposed beyond the first named head, one of the tubular needle members being permanently secured to the first named head, another tubular needle member being detachable with respect to the first named head, and said first named means including a split sleeve portion tensionally engaging the innermost needle member in retaining the same against accidental displacement from the other needle members.

5. A compound knitting needle of the class described, comprising an inner solid needle, other tubular needles telescoping with each other and the solid needle, all needles having one end thereof pointed, means forming a head at the other end of the tubular needles, all of said needles

including said head being composed of plastic material, and the solid needle having an independent head arranged outwardly of the first named head.

5. A compound knitting needle of the class described, comprising an inner solid needle, other tubular needles telescoping with each other and the solid needle, all needles having one end thereof pointed, means forming a head at the other end of the tubular needles, all of said needles including said head being composed of plastic material, the solid needle having an independent head arranged outwardly of the first named head, and means retaining the solid needle against accidental displacement from the head of said tubular needles.

6. A knitting needle structure of the class described comprising a plurality of needle members pointed at one end, part of the needle members being tubular to provide telescoping assemblage of the needle members one with respect to the other, means at the other end of the needle members for retaining the needle members in assembled relationship to each other, said last named means forming a head for the tubular needle members, the innermost needle member being in the form of a solid rod, and said innermost needle member having an independent head disposed outwardly of the first named head when the needle members are assembled.
